UNITED STATES PATENT OFFICE.

CHARLES A. SWEETLAND, OF CHICAGO, ILLINOIS.

DESIGN FOR A TRADE-COUPOON.

40,616.

Specification for Design.

Patented Apr. 5, 1910.

Application filed January 19, 1910. Serial No. 538,958. Term of patent 14 years.

To all whom it may concern:

Be it known that I, CHARLES A. SWEETLAND, a citizen of the United States, residing at Chicago, in the county of Cook and State of Illinois, have invented a new, original, and ornamental Design for a Trade-Coupon, of which the following is a specification, reference being had to the accompanying drawings, forming a part thereof.

The figure is a face view of a trade coupon, showing my design.

I claim:

The ornamental design for a trade coupon, as shown.

CHAS. A. SWEETLAND.

Witnesses:

SAMUEL P. WILSON,
NELSON R. SWEETLAND.
